UNITED STATES PATENT OFFICE.

JAMES S. DEELEY, OF CARYVILLE, MASSACHUSETTS, ASSIGNOR TO WILLIAM W. OLLENDORFF, OF MEDWAY, MASSACHUSETTS.

BOBBIN-HOLDER FOR SPINDLES OF SPINNING-MACHINES.

SPECIFICATION forming part of Letters Patent No. 665,384, dated January 1, 1901.

Application filed June 18, 1900. Serial No. 20,623. (Model.)

To all whom it may concern:

Be it known that I, JAMES S. DEELEY, a citizen of the United States, and a resident of Caryville, in the county of Norfolk and State 5 of Massachusetts, have invented a certain new and useful Bobbin-Holder for Spindles of Spinning-Machines, of which the following is a specification, reference being had therein to the accompanying drawings.

10 The invention relates to bobbin-holders more particularly adapted for use in connection with spindles of spinning-machines; and it has for its object to provide a simple, efficient, and durable means for holding the bobbin firmly and rigidly in its perpendicular position upon the spindle. No packing is necessary to hold the bobbin upon the spindle; neither is it necessary to hammer the bobbin down upon the same to keep it in its proper 15 position when my fastening device is used. Other objects and advantages of my invention will appear in the hereinafter-detailed description.

The invention consists, broadly, of metallic spring-arms rigidly attached to the spindle and extending outwardly therefrom and upwardly to receive and hold the bobbin, in combination with auxiliary springs. The invention also consists in providing the inner 20 faces of the said spring-arms with corrugations for the purposes hereinafter stated; and it further consists of the novel features of construction hereinafter set forth and described, and more particularly pointed out in 25 the claims hereto appended.

Referring to the drawings, Figure 1 is an elevation of the spindle, bobbin, and holder. Fig. 2 is an elevation at right angles to that shown in Fig. 1, partly broken away. Fig. 3 30 is a plan of the upper washer and spring, with spindle in section. Fig. 4 is a plan view of the lower washer and spring, and Fig. 5 is a central transverse section taken on the line 5 5 of Fig. 4.

45 Like letters of reference refer to like parts throughout the several views.

A denotes the spindle; B, the bobbin; C, the head of the bobbin, and D an annular groove in the same.

50 *a a* are spring-arms extending outwardly and upwardly from the spindle and so curved

and arranged that they will fit into the annular groove D, as shown in the drawings, Fig. 1 when the bobbin has been forced down between them to the desired point. 55

b b denote the auxiliary or reinforcing springs, the outer ends of which support the arms *a a*.

The spring-arms *a a* and the auxiliary 60 springs *b b* are preferably made of one piece of metal, the springs *b b* being formed by bending the metal of the spring-arms back upon itself until they come in contact with and touch the said arms *a a*. The metal used is preferably brass wire provided with corrugations *c c*, running lengthwise with the wire and on the inner side thereof, and in practice I find that three in number are sufficient for my purposes.

The spring-arms *a a* and the auxiliary 70 springs *b b* fit into grooves or reentering angles *d d*, cut in the washer *e*, which may be called the "lower" washer. These parts are rigidly attached to the spindle A by driving them down or swaging them upon the cone-shaped spindle until the desired point is reached. 75

f is a second washer, which may preferably be called the "upper" washer, which is likewise driven down upon or swaged upon the 80 spindle to hold the spring-arms and auxiliary springs firm and fast to the spindle. The upper surface of this washer *f* may be provided with spurs or teeth *g g* for clutching or biting the under side of the bobbin-head. 85

It is to be particularly noted that the auxiliary springs *b b* do not merely double the strength of the springs of the spring-arms *a a*, but they reinforce the same and by their joint action prevent the spreading of the arms *a a*, 90 for without the auxiliary springs, even if the gripping force of the spring-arms were doubled, the spring-arms would after a little use spread, thus causing the bobbin to slip and make it necessary to use packing to keep it 95 rigid on the spindle. The use of the auxiliary springs prevents this "spreading" absolutely, no matter how long the bobbin-holder is used, and makes a holder the gripping force of which practically suffers no depreciation by 100 use. Again, by this construction one can set the springs far enough under the bobbin-head

- so that the holder will hold a bobbin with a head a quarter of an inch smaller than will a holder with a single spring—that is to say, if there be put on a bobbin with a head large enough to open a single spring a quarter of an inch it will spread the spring of the holder so much that it will not come back to its original position, and when it is put onto the same holder it will slip, thus making it necessary to use a bobbin with a head much larger (about a quarter of an inch larger) than the one first used; but this is not the case when the auxiliary springs are used, for they tend to and do force the upper springs back to their original position, no matter if the same-sized bobbin is used over and over again.
- The corrugations *c c* on the inside of the spring-arms *a a* grip upon the side of the bobbin-head when the bobbin is forced down between the arms and will make a place for themselves on the side of the bobbin-head, thereby giving the arms a firmer hold on the same than if they were made of smooth wire or metal.
- 25 The mode of operation of the device in so far as it has not already been disclosed is as follows: To place the bobbin on the holder, the bobbin is forced down between the spring-arms *a a*, thus causing the springs *b b* to be slightly compressed and the inner corrugated sides of said arms to grip the sides of the bobbin-head, the upper part of said arms to fit slightly into the annular groove *D*, and the teeth *g g* to clutch or bite the under side of the bobbin-head. It will be found after this has taken place that it will be impossible to turn or twist the bobbin in the holder. To release the bobbin, it is only necessary to press it gently underneath until it is forced upwardly by the force of the springs, the auxiliary springs causing the spring-arms *a a* to resume their normal and original position.
- What I claim, and desire to secure by Letters Patent, is—
- 45 1. A bobbin-holder, comprising a spindle or other like device in combination with spring-arms and auxiliary springs acting upon said spring-arms, substantially as and for the purpose set forth.
- 50 2. A bobbin-holder, comprising a spindle or other like device in combination with two

spring-arms and an auxiliary spring for supporting each of said arms, substantially as described.

3. A bobbin-holder, comprising a spindle or other like device in combination with two spring-arms and an auxiliary spring for supporting each of said arms, each of said spring-arms with its supporting auxiliary spring being made of one piece of metal, a part of which is bent back upon itself to form the auxiliary spring.

4. A bobbin-holder, comprising a spindle or other like device in combination with spring-arms and auxiliary springs acting upon said spring-arms, the inner faces of said spring-arms being provided with corrugations, substantially as and for the purpose set forth.

5. A bobbin-holder, comprising a spindle or other like device, in combination with spring-arms *a a*, auxiliary springs *b b* applied to said arms, and washer *e* mounted upon the spindle and supporting the spring-arms and their auxiliary springs.

6. A bobbin-holder, comprising a spindle or other like device, in combination with spring-arms *a a*, auxiliary springs *b b* applied to said arms, washer *e* mounted upon the spindle and carrying the spring-arms and auxiliary springs, and washer *f* applied to the spindle and provided upon its upper surface with teeth, substantially as described.

7. A bobbin-holder, comprising a spindle or other like device, bobbin-gripping arms applied to said spindle and adapted to engage the bobbin, and a spring acting upon said arms to insure their gripping action, substantially as described.

8. A bobbin-holder, comprising a spindle or other like device, bobbin-gripping arms adapted to engage the bobbin and carry it around with the spindle, and a spring-support for said arms applied to the spindle, substantially as described.

In witness whereof I have hereunto affixed my signature, in the presence of two witnesses, this 16th day of June, 1900.

JAMES S. DEELEY.
